UNITED STATES PATENT OFFICE.

DAVID HOWELL, OF LOUISVILLE, KENTUCKY.

TRIP-HAMMER.

Specification of Letters Patent No. 27,804, dated April 10, 1860.

To all whom it may concern:

Be it known that I, DAVID HOWELL, of Louisville, Jefferson county, Kentucky, have invented a certain new and useful Improvement 5 in Trip-Hammers; and I hereby declare the following to be a full, clear, and exact description of the same, reference being had to the accompanying drawings, making part of this specification.

10 My invention consists in the employment for the lifting device of a trip hammer, of a cone cam constructed and arranged to slide on its driving shaft across that portion of the hammer on which the cam is brought to bear and adapted through lever or screw and a clutch between whose sides it is laterally confined to receive movement and adjustment while in motion, so that the lift and consequent force of the blow of the hammer 15 may be graduated to suit different work, or different stages of work under manipulation.

20 The accompanying drawing represents a perspective view of a trip hammer embodying my improvement.

A is the base or foundation of the hammer.

B are pillow blocks forming supports and fulcrum for the hammer C.

25 D are pillow blocks in which the cam driving shaft E rotates.

E is a cone cam constructed with regularly tapering sides and with longitudinal key slots fitting keys e on the shaft E so as to 30 permit the cam to slide freely upon the said shaft but prevent its rotation independently thereof.

G is a clutch adapted to slide in the bed plate A, and of such construction that the cam F may be laterally confined yet free to revolve between its sides g g'. It is provided with a rod H by which through lever, screw or other familiar device it may be operated, and any diameter of cone cam F brought in working connection with hammer 45 C while the machine is in motion, for the purpose as above described of regulating the height of lift.

I is the hammer head; J, the anvil block, and K the tail block.

50 The above described device is applicable to any point of raising or operating forging hammers.

I am aware that sliding or adjustable cams have previously been employed for 55 operating trip hammers with various lengths of stroke, but

I claim as new and of my invention and desire to secure by Letters Patent—

60 The arrangement of the sliding conical cam F feathered shaft E, sliding clutch G, rod H and hammer C, when the parts are constructed combined and adapted in the manner set forth to admit of varying the stroke of the hammer while in operation.

65 In testimony of which invention, I hereunto set my hand.

DAVID HOWELL.
